By Harold Payward Attorney.

UNITED STATES PATENT OFFICE.

BENJAMIN LOCKING, OF NAPIER, NEW ZEALAND.

APPARATUS FOR GENERATING VAPOR USED IN THE DESTRUCTION OF WEEDS AND RABBITS.

No. 807,180.

Specification of Letters Patent.

Patented Dec. 12, 1905.

Application filed March 18, 1905. Serial No. 249,973.

To all whom it may concern:

Be it known that I, BENJAMIN LOCKING, a subject of His Majesty the King of Great Britain and Ireland, residing in Tennyson 5 street, Napier, in the Provincial District of Hawkes Bay, in the Colony of New Zealand, have invented certain new and useful Improvements in Apparatus for Generating Vapor to be Used in the Destruction of Weeds and 10 Rabbits, of which the following is a specification.

This invention has for its object the generation of gas to be used for asphyxiating rabbits in their burrows and in the destruction 15 of weeds.

According hereto I employ a chamber in which sulfur or charcoal is placed and ignited. Air from a fan or the like is led into the chamber and a flexible pipe carries away the 20 resultant gas to the place where it is to be used. The end of the tube has a conical wire screen to prevent it from becoming choked when pushed into bushes or into a burrow.

The apparatus is mounted upon a barrow 25 for convenience in moving it from place to place.

Referring to the accompanying drawings, Figure 1 is a side elevation and Fig. 2 a plan. Fig. 3 is an enlarged sectional elevation of the apparatus removed from the barrow.

The combustion-chamber 1 is contained within the outer casing 2, the space 3 between the chamber and the casing being used to contain 35 water to prevent the chamber from becoming too hot. A tube 4, passing through the top of the casing into the chamber, is fitted with a cover 5, which is removable to allow the material from which the gas is to be generated to be placed in the chamber.

The apparatus is carried upon a barrow 6, and a fan 7 communicates with the chamber through a tube 8. The fan has a pulley 9 upon its axle which is revolved by a band 10, passing 45 around said pulley and around a driving-wheel 11, fixed upon a spindle 12, journaled upon the barrow and having a handle 13 by which it may be revolved.

A flexible metal tube 14 is connected to the 50 combustion-chamber 1 at one end and at the other end has a conical wire shield 15, which

is employed to prevent obstructive matter from entering the end of the tube. For convenience in operating the flexible tube handles 16, which may be of wood or covered 55 with non-conducting material, are secured upon a socket 17, fixed upon the tube 14.

My apparatus may be made of any metal which may be found most suitable for the purpose. The flexible tube is preferably that 60 known as "flexible metallic tubing," which is usually employed for carrying steam.

In operation sulfur or charcoal is placed in the combustion-chamber and ignited and the lid secured in position. The handle is then 65 turned, whereby the fan is revolved and air forced into the chamber, where it meets the burning sulfur or charcoal and forms sulfuric-acid or carbonic-acid gas, as the case may be. The destructive effect of the gas upon 70 weeds may in some cases be increased by first wetting the weeds with water by means of a spray-pump, which may be used in connection with my apparatus. For destroying weeds sulfuric-acid gas only is employed, and it is 75 led to the weeds by the tube 14. For destroying rabbits carbonic-acid gas or sulfuric-acid gas may be used, and the tube is inserted into the burrow, which is closed by packing earth or the like around the tube. When sufficient 80 gas has been driven into the burrow, the tube is withdrawn and the burrow completely closed, with the result that the rabbits therein are asphyxiated.

What I claim, and desire to secure by Letters Patent of the United States, is—

1. A device of the kind described comprising in combination, a combustion-chamber, a lid therefor, an outer casing receiving said chamber, a fan, a tube connecting said fan 90 with the combustion-chamber, a flexible delivery-tube one end of which is connected to the combustion-chamber and a conical wire shield for the end of said flexible tube substantially as specified.

2. A device of the kind described comprising in combination, a combustion-chamber, a lid therefor, an outer casing receiving said chamber, a fan, a tube connecting said fan with the combustion-chamber, a flexible delivery-tube one end of which is connected to the combustion-chamber and a conical wire

shield over the end of said flexible tube, a pulley on the fan - spindle, a driving - wheel fixed upon an axle, a handle for revolving said driving-wheel, a driving-band connecting said driving-wheel with the said pulley and a barrow upon which the apparatus is mounted substantially as specified.

In testimony whereof I have signed my name to this specification in the presence of two witnesses.

BENJAMIN LOCKING.
